(57) CLAIM

We claim the ornamental design for a decorative illuminated object, as shown and described.

DESCRIPTION

FIG. 1 is a front top perspective view of a decorative illuminated object showing our new design;

FIG. 2 is a rear bottom perspective view thereof;

FIG. 3 is a front view thereof;

FIG. 4 is a right side view thereof, the left side being a mirror image;

FIG. 5 is a rear view thereof;

FIG. 6 is a top view thereof; and,

FIG. 7 is a bottom view thereof.

Matter shown in broken lines does not form part of the design.
